UNITED STATES PATENT OFFICE.

ROWLEY K. ORTT, OF DIXON, ILLINOIS.

TAIL OR CONTROLLER FOR BOMBS.

1,282,709.

Specification of Letters Patent. Patented Oct. 22, 1918.

Application filed June 22, 1918. Serial No. 241,426.

To all whom it may concern:

Be it known that I, ROWLEY K. ORTT, a citizen of the United States of America, and resident of Dixon, county of Lee, and

5 State of Illinois, have invented certain new and useful Improvements in and Relating to Tails or Controllers for Bombs, of which the following is a specification.

This invention relates to certain improvements in bombs adapted to be dropped on the objective from air planes and other air craft; and the objects and nature of the invention will be readily understood by those skilled in the art in the light of the following explanation of the accompanying drawings illustrating what I now believe to be the preferred mechanical expression or embodiment of my invention from among other forms, constructions and arrangements within the spirit and scope thereof.

It is an object of my invention to provide bombs with improved means for increasing the accuracy of such bombs in landing on the objective against which they are directed from the air craft, and for maintaining such bombs in proper position while dropping from the air craft to assure discharge or explosion of the bomb when it strikes the ground or other objective.

30 With these and other objects in view the invention consists in certain novel features in construction, and in combinations and arrangements as more fully and particularly set forth and specified hereinafter.

35 Referring to the accompanying drawings:—

Figure 1, shows in elevation a bomb provided with my improved tail or controller.

Fig. 2, is a top plan.

40 Fig. 3 is a detail vertical section.

In the particular example illustrated, I more or less diagrammatically illustrate a bomb 1 of any suitable type or construction adapted to be dropped from air craft against an objective and provided with any suitable firing device designed to cause the bomb to explode when the objective is gained or when the bomb strikes the earth or any object. For instance, I show a firing pin or 45 pilot 2 at the front end or nose of the bomb designed to be operated by impact to bring about the explosion of the bomb.

In order to insure the landing of the bomb on its nose or in such other position 55 as may be necessary to require such operation of the firing pin or other device as to

cause the bomb to explode, and particularly to reduce to the minimum the curvature of the trajectory of the bomb in dropping from the air craft to the objective, I provide a 60 peculiar bomb tail or controller.

In the particular example illustrated, this tail consists of a straight shaft 3, at one end coupled to the rear end of the bomb by suitable coupling means, such as 4, and at 65 the opposite end having a propeller or fan of the required diameter or effective area, confined thereto to freely and concentrically rotate around said shaft as an axis.

The propeller consists of radiating uniformly-spaced similar flat twisted or inclined blades 5 having transversely inclined or angular faces and a center hub carrying said blades. The blades can be struck up or pressed from a single piece of flat sheet 75 metal so that the blades are integral with a flat center 6 having a center hole for the shaft. To the upper side of the flat center 6, a hub 7 is fixedly secured. The rear end of the shaft, if so desired, can have a tapered 80 portion and a threaded extremity 8. The hub is concentrically fitted on said shaft end and is confined thereon against longitudinal movement therefrom by one or more nuts 9 on the threaded shaft end or in any other 85 way or by any other means. Any suitable thrust as well as radial-thrust sustaining ball bearing 10 is arranged within the hub and interposed between the shaft and hub to permit free rotation of the propeller with 90 the least possible friction.

When the bomb is dropped or discharged from the air craft, the downward movement of the bomb causes rapid rotation of the propeller and the sustaining surfaces or area 95 thereof uphold the bomb in upright position through the medium of the shaft and coupling to the rear end of the bomb and the consequent drag on the rear end of the bomb, and yet the rapidly rotating propeller 100 permits such rapid descent of the bomb as may be required in practice.

Furthermore, the propeller rotated at high speed by its passage through the air, tends to resist lateral movement of the bomb from 105 the perpendicular and reduces the tendency of the bomb to follow a curved path from air craft to objective when delivered from air craft moving at high speed. In other words, the propeller coupled to the rear 110 end of the bomb by the shaft or other equivalent means, resists lateral movement of

the bomb and constantly acts to hold the bomb to movement in a straight perpendicular path from air craft to objective, with consequent accuracy in delivering the bomb 6 on the objective.

The bomber in the air craft, knowing the path that will be traveled by the bomb when dropped, can accordingly set and utilize his sighting instrument and deliver the bombs 10 with great accuracy.

I show the shaft 3, loosely or pivotally coupled to the bomb. If so desired, a snap hook 4 can be utilized for this purpose, whereby the shaft can be easily and quickly

15 applied to the bomb when the same is to be dropped from the air craft.

It is evident that various changes, modifications, and variations might be resorted to without departing from the spirit and scope 20 of my invention and hence I do not wish to limit myself to the exact disclosures hereof.

What I claim is:—

1. A tail or controller for bombs, comprising a freely rotatable propeller and its 25 axis and means for loosely coupling the axis to the rear end of a bomb against relative rotary movement with respect to the bomb and so that the propeller will trail behind the bomb substantially as described.

2. A tail or controller for bombs, comprising a shaft at one end formed for connection to the rear end of a bomb, and a propeller wheel confined on the opposite end of said shaft to freely rotate with respect thereto. 30

3. Means for the purposes substantially as described, comprising a shaft, a freely rotatable propeller wheel or fan loosely confined to said shaft, said shaft forming the fan axis and constructed and arranged for 40 coupling to a bomb, and a radial and end thrust ball bearing between the fan and shaft.

4. Means for the purpose substantially as described comprising a shaft at one end 45 formed and constructed for coupling to the rear end of a bomb, and a propeller or fan wheel freely rotatable on and confined to said shaft and embodying a hub and radiating blades having transversely inclined side 50 faces.

5. A bomb, in combination with a shaft at one end coupled to said bomb and adapted to trail behind the same when the bomb is descending, and a freely rotatable propeller 55 or fan wheel confined to and freely rotatable on said shaft.

ROWLEY K. ORTT.
